DOCKING STRUT

Ralph G. Peterson, Long Beach, Calif.

Application May 5, 1945, Serial No. 592,154

9 Claims. (Cl. 61—48)

(Granted under the act of March 3, 1883, as
amended April 30, 1928; 370 O. G. 757)

1

This invention relates to docking struts and more particularly to those designed to prevent damage to carrier type vessels.

Heretofore, the docking of an aircraft carrier or carrier type vessel has created a problem in spacing or fending the vessel a distance sufficient to prevent the overhanging superstructure, such as the flight deck and gun platforms, from interfering with the movement of cranes and other equipment on the pier and to prevent damage to said superstructure by such equipment.

Although target rafts, solid timber floats and similar means have been employed in attempts to accomplish the desired spacing or fending of the vessel from the pier, none have been successful due to the rigidity of such fenders, their cost and clumsiness as well as the inherent difficulties encountered in positioning and securing the same.

The principal objects of the present invention are therefore, to provide an improved docking strut for fending or spacing a carrier type or other vessel having an overhanging superstructure a sufficient distance from a pier to prevent damage to the superstructure and to eliminate interference with the movement of cranes and other equipment upon the pier by said superstructure, while permitting movement of the vessel without damage to the same or the strut; to provide an improved docking strut having limited flexibility so as to be capable of movement with a docked vessel relative to the pier; to provide an improved docking strut which is so constructed as to distribute the loads imposed by excessive shifting of the vessel over a considerable area of the pier or upon a number of its fender piles; to provide an improved docking strut having an adjustable bearing surface so as to conform to the shape of the hull of the docked vessel, thereby preventing damage to said hull; to provide an improved docking strut which may be readily moved into and out of fending position to permit the docking of all types of vessels; and to provide improved elements and arrangements there-in in a docking strut of the character and for the purpose set forth.

In accomplishing these and other objects of the invention, I have provided improved details of structure, the preferred form of which is illustrated in the accompanying drawing, wherein:

Fig. 1 is a diagrammatic plan view of a plurality of docking struts, embodying the features of the present invention, mounted upon the camel logs of a pier and having their camel logs bearing against the hull of a vessel.

2

Fig. 2 is an enlarged plan view of one of the docking struts, showing its details of construction and its connection to the camel logs.

Referring more in detail to the drawing:

In Fig. 1, the numeral 1 designates the usual upright fender piles of a pier (not shown) which have generally cylindrical timbers or members 2, of wood and commonly referred to as camel logs, fastened thereto at approximately the water line so as to float and be self-supporting. The members 2 are disposed horizontally in axial alignment and are preferably spaced a slight distance from each other. A plurality of docking struts or assemblies 3, preferably three in number, are adapted to be fastened to the members 2 and project laterally therefrom for spacing or fending the hull of a vessel of carrier or other type from the pier a distance sufficient to prevent damage to the overhanging superstructure of the vessel.

such as the flight deck and gun platforms of an aircraft carrier, as well as to prevent such superstructure from interfering with the movement of cranes and other equipment upon the pier. Manifestly, the quantity of the struts or assemblies is not critical and, in some instances, it might be desirable to employ a greater or fewer number of the same.

As is clearly shown in Fig. 2, each strut or assembly 3 preferably includes a pair of horizontal elements or arms 4, of any suitable material, having their outer ends converging and pivotally connected to a clamping bracket 5 by pivot pins 6 which are suitably mounted in the bracket adjacent each end thereof. A similar clamping bracket or plate 7 is pivotally connected by a pivot pin 8 to the inner end of each arm 4 for securing the same to one of the members 2. Each plate 7 is of relatively short length and is disposed contiguously to the outer lateral portion of its respective member 2, preferably being connected thereto by a pair of tie bolts 9 and encircling wire lines 10 which are disposed at the ends of the plate. If desired, the member 2 may be recessed or cut away as shown by the numeral 11 for receiving the lines 10 and permitting the same to lie flush with the exterior of said member. Attention is directed to the fact that each plate 7 is preferably disposed adjacent one end of its member 2 so as to dispose the bracket 5 in substantial alignment with the space between adjacent members and thereby distribute the load between said members and their respective piles 1, as will be hereinafter more fully explained.

A connecting truss or link 12 is disposed between the inner ends of the arms 4 in approx-

imately contiguous, parallel relation to the members 2 and is fastened to said arm ends by suitable eye bolts 13 which are carried by the arms and connected to the ends of the link by pivot pins 14. Thus, the arms 4 may move or pivot horizontally relative to the link 12 and said link functions primarily to space and hold the plates 7 in a fixed position relative to each other.

For fending or bearing against the hull H of the ship to be docked, a cylindrical wooden member or camel log 15 is adapted to be fastened to the outer lateral surface of the bracket 5 by means of a pair of tie bolts 16 and wire lines 17 so as to be disposed horizontally of and parallel to the members 2. The log 15 preferably has its medial portion secured to the bracket 5 so as to project equally beyond each end thereof and may be recessed or cut away as shown by the numeral 18 for receiving the wire lines 17 and permitting the same to lie flush with the exterior of said log. As shown in Fig. 1, the log 15 is preferably of considerably less length than the members 2. A diametric opening 19 is formed in each end of the log 15 for receiving a wire line 20 which has a stabilizing line 21 connected thereto, whereby the ends of the log may be swung manually slight distances in a horizontal plane due to the provision of the pivot pins 6, 8 and 14 and the limited pivotal movement of the arms 4. A suitable cleat 22 is provided at the inner end portion of each arm for permitting the securing of the lines 21 and the holding of the arms and log 15 in relatively fixed positions.

When the docking struts are not necessary for certain types of vessels, it is desirable to alter their position or remove them entirely from their functional position shown. To this end, I have provided a convenient arrangement which preferably includes a hollow tank or float 23 that may be pivotally secured by suitable straps 24 between the outer end portions of the arms 4 adjacent the bracket 5 to allow movement thereof with the strut. The float 23 preferably has a valved inlet 25 communicating with its interior through one side wall thereof. A flexible conduit or hose 26 is suitably connected in the inlet 25 for conducting air, water or other fluid under pressure to the interior of the float from a suitable pump (not shown) which may be mounted on the pier. Although not illustrated, the valve of the inlet 25 is preferably of the back-pressure type so as to admit fluid under pressure while preventing the escape of such fluid. A valved outlet 27 is formed in the opposite side wall of the float and has a spring-pressed check valve (not shown) mounted therein for preventing the escape of fluid below a predetermined pressure from the interior of the float. By filling the float with air, it will have sufficient buoyancy to support the strut in a horizontal position. Although the log 15 has sufficient buoyancy to be self-supporting, it does not support the weight of the entire strut and particularly the float 23 when the latter is filled with water. In order to submerge the strut, it is necessary to pump or force water or other liquid into the interior of the float through the hose 26 and inlet 25, thereby opening the check valve (not shown) and forcing the air out through the outlet 27.

Operation

The operation of a docking strut constructed as described is as follows:

Upon the docking of a vessel of the carrier

or other type having an overhanging superstructure, such as the flight deck and gun platforms of an aircraft carrier, the docking struts 3 are swung into horizontal position as shown in Fig.

- 5 1. Although the struts might be removed and stored when not in use, it is preferable to employ the floats 23 for submerging and raising said struts by swinging or pivoting the same vertically about the members 2. It is ordinarily necessary to loosen the eye bolts 9 and the ropes 10 in order to permit this vertical movement of the struts as well as circumferential movement of the plates 7 about the members 2. When the struts are submerged, the floats contain water or 15 other liquid and the weight of said struts or their floats is sufficient to overcome the buoyancy of the camel logs 15. Thus, the struts are disposed close to the lower or underwater portions of the fender piles 1. In order to exhaust 20 the water or liquid from each float, air is pumped or forced through each hose 26 and inlet 25. When the pressure within the float builds up sufficiently to overcome the pressure of the spring resisting opening of the check valve of 25 the outlet 27, said valve opens to permit the ejection of said water or liquid through said outlet. The escape of the water or liquid from the floats is facilitated by the outlets 27 being disposed beneath their respective floats upon submergence or vertical disposition of the struts. 30 Upon the filling of the floats with air and the exhaustion of the water or liquid therefrom, the struts swing or pivot upwardly to the horizontal floating position illustrated. A ship of the carrier or other type, having an overhanging superstructure, may be readily docked and properly spaced from the pier when the struts are in such position.

- 35 Due to the horizontal pivotal mounting of the 40 arms 4, the camel logs 15 are permitted to turn or pivot in a horizontal plane so as to conform to the shape of the ship hull H. After this conformity of the logs and the docking of the ship, the lines 21 may be secured to the cleats 22 to 45 prevent said logs from altering their positions. The logs fend or bear against the hull H as shown in Fig. 1 so as to prevent damage to or marring of said hull by the struts and move limited distances with the hull. Since each strut 50 is connected to at least two camel logs or members 2 and since the latter are carried by a plurality of the fender piles 1, it is readily apparent that the loads imposed upon the struts are distributed throughout a relatively large area of the 55 pier so as to prevent undue strains upon the latter.

- 60 As has been hereinbefore pointed out, the struts space the hull H a sufficient distance from the pier to prevent damage to the superstructure of the ship by the movement of cranes or other equipment upon the pier. Also, the ship's superstructure does not interfere with the movement of such equipment. When not in use or when 65 it is desired to dock a ship not having an overhanging superstructure, the struts are moved or swung out of their horizontal or lateral position and this movement is preferably accomplished by filling each float 23 with water. The air is exhausted through the opening 27 by forcing water 70 or liquid under pressure through the hose 26 and inlet 25. Upon filling of the floats with water, the weight of the struts overcomes the buoyancy of the logs 15 so as to sink or submerge said struts and cause the same to depend vertically from the members 2 adjacent the piles. Atten-

tion is again directed to the fact that the number of struts employed is subject to variation, although three have been found to be adequate.

From the foregoing, it is readily apparent that a docking strut has been provided which has sufficient flexibility to be particularly adaptable for use in fending or spacing vessels having overhanging superstructures so as to prevent damage to said superstructures or interference with the movement of equipment upon the pier and which is so constructed and supported that the loads imposed upon the strut are distributed throughout a considerable area of said pier.

I have described one embodiment of my invention. However, it will be apparent that the device is susceptible to numerous modifications without departing from the spirit of the invention. Therefore, I do not wish to be limited by the disclosure set forth hereinbefore, but only by the scope of the appended claims.

The invention described herein may be manufactured and used by or for the Government of the United States of America for governmental purposes without the payment of any royalties thereon or therefor.

I claim:

1. A docking strut fastened to a pier including, a horizontal frame of substantially triangular shape, the frame having a pair of outwardly directed converging arms, a pair of plates pivotally connecting the inner ends of the arms to the pier, a bracket pivotally connecting the outer ends of said arms to each other, a link pivotally connected between the inner ends of the arms for spacing the same relative to each other, and a floating member secured to the bracket and disposed horizontally for bearing against the hull of the vessel to be docked.

2. A docking strut fastened to a pier including, a horizontal frame of substantially triangular shape, the frame having a pair of outwardly directed converging arms, a pair of plates pivotally connecting the inner ends of the arms to the pier, a bracket pivotally connecting the outer ends of said arms to each other, a link pivotally connected between the inner ends of the arms for spacing the same relative to each other, a floating member secured to the bracket and disposed horizontally for bearing against the hull of the vessel to be docked, and stabilizing lines extending between the outer ends of the bearing member and the inner ends of the frame arms.

3. A docking strut fastened to a pier including, a horizontal frame of substantially triangular shape, the frame having a pair of outwardly directed converging arms, a pair of plates pivotally connecting the inner ends of the arms to the pier, a bracket pivotally connecting the outer ends of said arms to each other, a link pivotally connected between the inner ends of the arms for spacing the same relative to each other, a floating member secured to the bracket and disposed horizontally for bearing against the hull of the vessel to be docked, and a hollow float carried by portions of the frame arms and adapted to be filled for submerging and swinging the frame downwardly relative to the pier, the pair of plates being adjustably secured to the pier so as to permit loosening of said plates and downward swinging of said frame.

4. A docking strut fastened to a pier including, a horizontal frame of substantially triangular

shape, the frame having a pair of outwardly directed converging arms, a pair of plates pivotally connecting the inner ends of the arms to the pier, a bracket pivotally connecting the outer ends of said arms to each other, a floating member secured to the bracket and disposed horizontally for bearing against the hull of a vessel to be docked, and stabilizing lines extending between the outer ends of the bearing member and the inner ends of the frame arms.

5. A docking strut secured to a pier including, horizontally-aligned outwardly-directed elements pivotally connected to the pier, a member for bearing against the hull of a vessel to be docked, means for vertically pivotally connecting the bearing member to the outer ends of the elements whereby said bearing member is adapted to undergo pivotal movement about a substantially vertical axis, and stabilizing lines extending between the outer ends of the bearing member and the inner portions of said elements.

6. A docking strut secured to a pier including, a substantially horizontal frame of generally trapezoidal shape, the frame having a pair of lateral outwardly converging elements pivotally connected to the pier, means pivotally connecting the outer portions of the elements so as to permit horizontal movement of said elements relative to each other, and a member fastened to said elements by the pivotal connecting means for bearing against the hull of a vessel to be docked, the member being pivotable horizontally so as to be movable with said vessel relative to said elements.

7. A docking strut secured to a pier including, a pair of elements pivotally connected to the pier and arranged laterally thereof, and a horizontal bearing member having pivotal connection with the outer ends of the elements so as to be movable in a horizontal arc relative to said elements.

8. A docking strut secured to a pier including, a pair of elements pivotally connected to the pier and extending laterally thereof so as to undergo pivotal movement in a horizontal plane, and a horizontal member having pivotal connection with the outer ends of the elements for bearing against the hull of a vessel to be docked and being pivotable relative to said elements in a horizontal plane.

9. A docking strut secured to a pier including, horizontally-aligned outwardly-directed elements pivotally connected to the pier so as to be movable in a horizontal plane, a horizontal member for bearing against the hull of a vessel to be docked, and means for pivotally connecting the bearing member to the outer ends of the elements whereby said member is pivotable in a horizontal plane relative to said elements and pier so as to substantially conform to the shape and movement of the vessel.
